UNITED STATES PATENT OFFICE.

CLYDE C. BALSTON, OF NEW YORK, N. Y.

TRANSMITTING MECHANISM.

Application filed April 8, 1927. Serial No. 182,140.

The object of my invention is to provide simple and efficient means for transmitting motion from a moving or driving member to a member or object to be moved or driven, where said members are not wholly located in a straight line, and whereby a pull of the moving or driving member on an intermediate connection is to be transmitted thereby to the member to be moved or driven.

10 My invention comprises novel details of improvement and combination of parts that will be more fully hereinafter set forth and then pointed out in the claims.

Reference is to be had to the accompanying drawings forming part hereof, wherein,

15 Figure 1 is a side elevation, partly broken and parts omitted, of a transmitting mechanism embodying my invention;

Figure 2 is a partly broken plan view 20 thereof;

Figure 3 is a section on the line 3, 3, in Figure 2;

25 Figure 4 is a detail perspective view of one of the caps for guiding the flexible connection;

Figure 5 is a section on the line 5, 5, in Figure 1;

Figure 6 is a detail section on the line 6, 6, in Figure 1; and

30 Figure 7 is a detail of a modification.

Similar numerals of reference indicate corresponding parts in the several views.

The numeral 1 indicates a portion of a suitable frame, upon which one or more plates or the like 2 are carried, which plates are shown arranged substantially on edge. I have shown means for adjustably supporting plates 2 on frame 1 so that said plates may be laterally adjustable, and may be retained in set position either vertically on edge or at an angle to the vertical as desired. For this purpose the frame 1 is shown provided with laterally disposed threaded rods 3 that are received in threaded holes in the uprights of frame 1, the plates 2 having holes through which the rods 3 freely pass, and upon said rods are pairs of nuts 4, on opposite sides of the plates 2, whereby said plates may be adjusted along rods 3 and held firmly in set positions. The nuts are shown provided with convex faces that bear upon plates 2, enabling said plates to be maintained in inclined positions, as in

Figure 5. It will be understood that rods 3 with their nuts are located at opposite ends 55 of plates 2, said parts being shown at one end only of plates 2 for simplicity of illustration. Upon the plates 2 are located a plurality of series of spaced guides 5, which have curved peripheries at the working 60 parts, provided with grooves 5^a that receive flexible connections 6, that are intended to transmit motion from a moving or driving member to a member to be moved or driven. While the guides 5 may be formed integrally 65 with plates 2, in the arrangement illustrated the guides 5 are shown in the form of suitable blocks provided with slots 5^b, through which screws 7 freely pass and enter threaded apertures in plates 2, whereby the guides 5 70 may be adjusted to vary the tension on or to take up slack that may occur in, the connections 6. While for some uses it may not be necessary to cover the grooves 5^a of guides 5, yet for other uses it may be desirable or 75 necessary so to do, and to this end I provide guiding caps 8, shown in the form of plates fitted at the sides of guides 5 and having lateral flanges 8^a, curved to substantially follow the corresponding curved contour of 80 the guides 5, and adapted to overlie the grooves 5^a thereof, said flanges 8^a being suitably cut away at 8^b to permit the free passage of the connections 6 (see Fig. 4). The caps 8 are provided with slots 8^c to receive 85 the screws 7 permitting adjustment of the caps with the guides 5. The positions of the cut away parts 8^b of the flanges 8^a will accord with the approximate points at which the connections 6 leave or make contact with 90 the guides 5 respectively, according to the angles of the connections 6 with respect to said guides. Instead of the guides 5 being stationary they may be rotative, as illustrated at 5^d in Figure 7, to reduce friction on 95 the connections 6 as the latter are operated. In the example illustrated I have shown a plurality of guides 5 on opposite sides of a centrally disposed flexible connection 6^a (Figure 1), that may pass operatively in a 100 straight line without requiring a guide 5. The curved working peripheries of the guides 5 on one side of connections 6^a are all shown disposed as at the left hand sides of the guides, and the curved peripheries of the 105 guides 5 on the other side of said connections

6^a are shown disposed toward the right hand side, whereby the connections 6 passing from opposite sides of the center of the guides 5 may all be brought to a position approximately close together as compared with the spaces between the working surfaces of the guides 5. To this end the flexible connections 6 pass through curved guides shown in the form of guiding grooves 9, shown formed 10 in block 10 secured upon plates 2 on the same side as and above the corresponding guides 5, the grooves 9 on one side of the central connection 6^a all being curved in one general direction reverse to the working surfaces of 15 the corresponding guides 5, and the grooves 9 on the other side of the connection 6^a being all grooved in a direction reverse to the first named grooves 9, and also reverse to the working surfaces of the corresponding 20 guides 5. By the arrangement shown the upper ends of the guides 9 may all be spaced apart equal distances.

To retain the connections 6 in the grooves 9 I have shown a plate 11 over each block 25 10, which plates and blocks may be retained in place by screws 12. (Figures 2 and 5). Plate 11 is broken away in Figure 1 for clearness of illustration. Beyond or above the guiding grooves 9 the flexible connections 6, 6^a are guided in the required direction to members to be operated by or to operate said connection. To this end I have shown blocks 13 having curved guiding 30 grooves 13^a (Figure 3) receiving the connections 6, 6^a, the grooves 13^a being shown spaced apart corresponding to the grooves 9, the grooves 13^a serving to properly guide the connections 6, 6^a with respect to grooves 9. Blocks 13 are shown mounted upon a 35 suitable part 1^a of frame 1 above the plates 2 and held in place by screws 14. The connections 6, 6^a are shown broken to indicate that they may be of any desired length, and in Figure 1 I have shown several connections 40 provided with turn-knuckles 15 to take up slack in the connections. Any or all of such connections may be provided with turn-knuckles if desired. The flexible connections 45 6, 6^a may be in the form of relatively thin flat strips of suitable metal, such as flat wire, or of round wire, chain or cable. For some uses it may be preferable to provide said connections of thin flat metal strips or 50 flat wire, affording the required flexibility 55 without danger of undue stretching. Such flat strips will properly slide on the working surfaces of the guides 5 and 9 in a flatwise manner, and yet will suitably twist in the space between the guides 9 and grooved 60 blocks 13 where such strips, adjacent to the upper edges of guides 9, are edgewise to the planes of the blocks 13, so that said strips will lie flatwise in the grooves 13^a, and particularly where such strips pass to or from 65 the blocks 13 in an angular direction with re-

spect to said blocks and the guides 9. Such construction is shown in Figure 3.

From the foregoing description it will be understood that by means of my improvements a simple and efficient mechanism is 70 provided to enable, for instance, devices from which power or motion are to be transmitted, and which are necessarily somewhat spaced apart, to be connected with and to operate other devices which are required to 75 be relatively close together, and whose proximity to one another would preclude the convenient use of a plurality of closely related devices, such as shafts and levers, arms, or the like, for operating the same. My improvements, therefore, enable the various flexible connections that pass over or along the relatively widely spaced guides 5 to converge to, or diverge from the closely related guides 9, and yet portions of the connections 80 6, 6^a on one or both sides of the guides 5 and 9, may pass in substantially parallel lines to one or more of their operating or operated members.

My improvements may be utilized for operating devices for controlling type printing wheels in writing machines, as in word and phrase writing machines, and may be used for transmitting movement from the arms 95 39 set forth in Letters Patent No. 1,612,089, granted to me December 28, 1926, on mechanical movements, to any desired parts to be controlled, by suitably connecting the flexible connections 6, 6^a with said arms, as for controlling the stops and type wheels in 100 a word or phrase writing machine. Said flexible connections may also be utilized for operating appropriate parts in linotype or type setting machines, or in mechanism for transmitting electric impulses, such as telegraph typewriters, and for any other purposes, and in signalling and switching devices for railway and other signal systems, and in other relations where simple direct 105 acting means are desired for transmitting 110 movement to or from associated devices that are more or less close together.

While I have shown two sets of similar devices carried by the two plates 2, organized in a single structure, it will be understood that one or more of said sets of devices 115 may be used in a single mechanism if desired.

My invention is not limited to the particular details of construction set forth, as the 120 same may be varied, within the scope of the appended claims, without departing from the spirit of the invention.

Having thus described my invention, what I claim and desire to secure by Letters Patent is:

1. A transmitting mechanism comprising a plurality of spaced guides, a second plurality of guides spaced nearer together than the spacing between the first named guides, 120

- the second named guides having curves of varying diameters, and flexible connections passing along said guides.
2. A transmitting mechanism comprising a plurality of spaced guides, and a second plurality of spaced guides located between the extremes of the first named guides and spaced apart distances less than the spacings between the first named guides, the second named guides having curves of varying diameters, and flexible connections passing along said guides.
3. A transmitting mechanism comprising a plurality of spaced guides, a second plurality of guides spaced nearer together than the spacing between the first named guides, the second named guides having curves of varying diameters, flexible connections passing along said guides, and means having guiding grooves adjacent to the second named guides to receive said flexible connections.
4. A transmitting mechanism comprising a plurality of spaced guides, caps for said guides, a second plurality of guides spaced nearer together than the spacings between the first named guides, and flexible connections passing along said guides and guided by said caps.
5. A transmitting mechanism comprising a plurality of spaced guides, caps for said guides having flanges provided with openings, a second plurality of guides spaced nearer together than the spacing between the first named guides, and flexible connections passing along said guides and through the openings of said caps.
6. A transmitting mechanism comprising a plurality of spaced guides, and caps on the sides of said guides and having flanges extending transversely across said guides, said flanges having openings, and flexible connections passing along said guides and through the openings of said caps.
7. A transmitting mechanism comprising a support, a plurality of guides spaced apart upon said support, means for adjustably retaining said guides upon said support, a second plurality of guides upon said support and spaced apart distances less than the spacings between the first named guides, and flexible connections passing along said guides.
8. A transmitting mechanism comprising a plurality of spaced guides, certain of said guides having grooved peripheries facing in one direction on one side of the center of the guides, the guides on the other side of said center having grooved peripheries facing in opposite directions, a second plurality of guiding grooves, said grooves on opposite sides of said center facing reversely to the first named guides on corresponding sides of said center, and flexible connections passing along said guides.
9. A transmitting mechanism comprising a plurality of spaced guides, a block having guiding grooves that are nearer together than the working surfaces of the first named guides, said grooves and the corresponding first named guides on one side of their center facing reversely to each other and to those on the other side of the center, flexible connections passing along said guides and grooves, and means to retain said connections in said guiding grooves.
10. A transmitting mechanism comprising a plurality of spaced guides, a second plurality of guides spaced nearer together than the spacings between the first named guides, a block having guides located on the side of said second named guides opposite to the first named guides, and flexible connections passing along said guides.
11. A transmitting mechanism comprising a frame, a plate, means for supporting the plate for lateral adjustment, a plurality of spaced guides carried by said plate, a second plurality of spaced guides carried by said plate, and flexible connections passing along said guides.
12. A transmitting mechanism comprising a frame, a plate, means for supporting the plate for lateral adjustment, a plurality of spaced guides carried by said plate, a second plurality of spaced guides carried by said plate, the second named guides being nearer together than the first named guides, and flexible connections passing along said guides.
13. A transmitting mechanism comprising a frame, threaded rods carried by the frame and spaced apart, a plate loosely receiving said rods, nuts upon said rods for adjustably sustaining said plate in different positions, a plurality of spaced guides carried by said plate, a second plurality of spaced guides carried by said plate above the first named guides, and flexible connections passing over said guides.
14. A transmitting mechanism comprising a frame, threaded rods carried by the frame and spaced apart, a plate loosely receiving said rods, nuts upon said rods for adjustably sustaining said plate in different positions, a plurality of spaced guides carried by said plate, a second plurality of spaced guides carried by said plate above the first named guides, spaces between one set of guides being less than the spacing between the other set of guides.
15. A transmitting mechanism comprising a frame, threaded rods carried by the frame and spaced apart, a plate loosely receiving said rods, nuts upon said rods for adjustably sustaining said plate in different positions, a plurality of spaced guides carried by said plate, a second plurality of spaced guides carried by said plate above the first named guides, spaces between one

set of guides being less than the spacing between the other set of guides, and a block above said plate provided with a plurality of guiding grooves receiving said connections.

16. A transmitting mechanism comprising a plurality of spaced guides, a second plurality of guides spaced nearer together

than the spacing between the first named guides, a block having guides located on the side of the second named guides opposing the first named guides, and relatively thin flat flexible connections passing over said guides and twisted between said block and said second named guides.

CLYDE C. BALSTON.
